UNITED STATES PATENT OFFICE.

ARTHUR C. GROVER, OF PAINESVILLE, OHIO, ASSIGNOR OF ONE-THIRD TO HARRY E. BARNES AND ONE-THIRD TO CHARLES SANBORN, BOTH OF WILLOUGHBY, OHIO.

ADVERTISING DEVICE.

1,355,664.

Specification of Letters Patent.

Patented Oct. 12, 1920.

Application filed December 30, 1919. Serial No. 348,315.

To all whom it may concern:

Be it known that I, ARTHUR C. GROVER, a citizen of the United States, residing at Painesville, in the county of Lake and State 5 of Ohio, have invented certain new and useful Improvements in Advertising Devices, of which the following is a specification.

This invention relates to improvements in advertising devices of that type in which a 10 series of movable curtains or exhibitors are successively moved into a position visible behind an opening in a casing, and the principal object of the invention is the provision of especial and efficient means for intermittently and successively moving the display 15 curtains into position behind the display opening.

Another object of the invention is the provision of an advertising device of this type 20 in which the display curtains are compactly arranged to economize in the space occupied thereby and permit the utilization of a greater number of curtains in a given space.

With these and other objects in view as 25 will appear as the description proceeds the invention comprises the novel features of construction, accompanied by elements and arrangement of parts which will be more fully described in the following specification 30 and set forth with particularity in the claims appended hereto.

Figure 1 represents a front elevation of the advertising device,

Fig. 2 represents a vertical transverse sectional view therethrough,

Fig. 3 represents a vertical sectional view taken at right angles to Fig. 2, in the plane of the front portion of the slot accommodating the rods of the curtains,

Fig. 4 represents a horizontal sectional view on the line 4—4 of Fig. 2,

Fig. 5 represents a detail sectional view on the line 5—5 of Fig. 2,

Fig. 6 represents an enlarged fragmental sectional view of one upper corner of the casing, and,

Fig. 7 represents a detail of one of the drive chains, dog and curtain rod.

Referring to the drawing in detail, where- 50 in similar reference characters designate corresponding parts throughout the several views, the numeral 5 indicates a casing provided in the front wall 6 with a display opening 7 through which the advertising or other matter marked upon the movable curtains is visible.

A roller 8 is supported adjacent the front upper portion of the casing and its terminals are journaled in partitions 9 which are arranged adjacent the opposite side walls of 60 the casing and provide lateral chambers 10 for the reception of the drive chains, to be hereinafter described.

The roller 8 supports a plurality of curtains 11 which are constructed of a durable 65 and flexible material and are preferably detachably connected with the roller 8 by an approved type of fastener whereby the respective curtains may be interchanged or removed and replaced from time to time. The 70 terminals of the curtains opposite the roller 8 are connected with rods 12 movable in the slots 13 formed in the partitions 9 and of such length as to project into the lateral 75 chambers 10. Each slot 13 is of polygonal form and includes the front vertical portions 14, relatively narrow bottom horizontal way 15, inclined rear portion 16 which extends upwardly toward the back of the casing 5 and connects by horizontally disposed portion 17 to the upper terminal of the front 80 vertical portion 14 forming a continuous passage through which the rods 12 are successively moved during operation of exhibitor.

The several rods are interconnected by flexible chains 18 arranged inside of the partitions 9 and of a length approximately corresponding to the length of the curtains 11. The majority of the rods 12 normally lie in 90 the relatively short horizontally disposed slotted portion 15 and the chains 18 depend therefrom into the lower portion of the casing. The chains connecting the front and rear rods of the group which is disposed 95 within the relatively short horizontal flat portion 15 extend upwardly from the rear-most rod over a guide wheel 19, forwardly and downwardly over the extremities of the roller 8 to the front rod of the group there- 100 by forming endless chains connecting the terminals of the rods at each side of the casing and causing the curtains to be successively drawn upwardly toward the rear of the casing, forwardly under the top and 105 downwardly along behind the display opening 7.

Endless drive chains 20 are arranged in the chambers 10 and extend over sprocket wheels 21 supported adjacent the four cor- 110 ners of the chambers upon shafts 22. The lower rear shaft 22 is connected by a train

of gears 23 with the drive shaft 24 of an electric motor 25 whereby power is applied to the chains to constantly actuate the curtains for a prolonged period. Inwardly directed dogs 26 are secured at corresponding points to the two chains 20 and are engageable with the terminals of the rod 12 lying at the upper terminal of the vertical portion 14 of the slot so as to draw the rod 12 down and move the curtain attached thereto into display position behind the opening 7, the chain connecting the downwardly moving rod with the next successive rod operating to draw the latter to the position at the upper terminal of the slot 14 previously occupied by the downwardly moving rod. The dog 26 engages the terminals of the rod 12 at the upper terminal of the slot 14 each time the chains complete a trip over the sprocket wheels 23 and in this manner the several exhibiting curtains are successively moved into position behind the opening 7 and during the period of concealment the curtains are compactly arranged in a group depending from the roller 8, as clearly shown in Fig. 2. It will be understood that as the rod 12 moves into the relatively short horizontal slot portion 15 it moves out of the path of the dog 26 permitting the latter to pass unobstructed and owing to the length of the chain and the time consumed in the dog traveling between the series of rods 12 and the roller 8, the respective curtains are left visible for a period of time sufficient for the average person to read or appreciate the matter marked thereon.

What I claim is:

1. In combination, a casing having a display opening in the front wall thereof, a roller supported in the casing, a plurality of flexible display curtains supported by the roller successively movable to display position behind said opening, means to successively engage and move the curtains into display position behind the opening, and connections between the terminals of the curtains opposite the roller whereby the movement of one curtain is transmitted to the other during the movement of the respective curtains.

2. In combination, a casing having a display opening therein, a roller supported in the casing, a plurality of flexible curtains attached at one end to the roller successively movable to display position behind said opening, rods connected with the opposite terminals of the curtains, means for guiding the movement of the rods through the casing, flexible connections between said rods, guide means for said flexible connections, and means engageable with the terminals of the rods for successively bringing the curtains into display position behind the opening.

3. In combination, a casing having a display opening therein, a roller supported in said casing, a plurality of flexible curtains supported by said roller successively movable to display position behind said opening, rods carried by the terminals of the curtains, means for guiding the movement of the rods through the casing, means engageable with the rods for successively bringing the latter into display position behind the casing opening, and connections between the rods whereby the movement of one curtain is transmitted to the succeeding curtain.

4. In combination, a casing having a display opening, a plurality of flexible curtains supported by said roller successively movable to display position behind said opening, rods carried by said curtains, means for guiding the movement of the rods, means engageable with a rod lying in a position above the display opening for depressing the rod and moving the curtain carried thereby into display position, and connections between the rods whereby the movement of one curtain is transmitted to the next succeeding one.

5. In combination, a casing having a display opening, therein, a roller supported in the casing, a plurality of flexible curtains attached at one end to the roller and located behind the opening successively movable to display position behind said opening, rods carried by the curtains, means for guiding the rods downwardly in front of the roller, upwardly behind the latter and forwardly above the roller, drive chains arranged adjacent the ends of the rods, and dogs carried by the chains engageable with the rods as the latter reach a predetermined location in the casing whereby the curtains are successively moved into display position behind the opening.

6. In combination, a casing having a display opening therein, a roller supported in the casing, a plurality of flexible display curtains supported by the roller successively movable to display position behind said opening, rods carried by the curtains, guide means for the rods, chains arranged outwardly of the ends of the rods, dogs carried by the chains engageable with the terminals of the rods as the latter approach a predetermined location within the casing whereby the curtains are successively moved into display position behind the opening, and means connecting the rods whereby the movement of one rod is transmitted to the succeeding rods to successively draw the rods into dog engaging position.

In testimony whereof, I affix my signature hereto.

ARTHUR C. GROVER.
